UNITED STATES PATENT OFFICE.

JOHN HEIMER, OF MINNEAPOLIS, MINNESOTA, ASSIGNOR TO MINNESOTA MANUFACTURERS ASSOCIATION, A CORPORATION OF MINNESOTA.

ELEVATOR.

1,046,386.

Specification of Letters Patent.

Patented Dec. 3, 1912.

Application filed July 9, 1906. Serial No. 325,288.

To all whom it may concern:

Be it known that I, JOHN HEIMER, a citizen of the United States, residing at Minneapolis, in the county of Hennepin and State of Minnesota, have invented certain new and useful Improvements in Elevators; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to elevators of the class used in ware-houses and similar places for hoisting and lowering boxes from one floor to another without reversing the motion of the elevator, and which are capable 20 of loading and unloading themselves while in motion; and the objects are to provide a cheap, durable and efficient elevator of said class. These and other objects I attain by the novel construction and arrangement of 25 parts illustrated in the accompanying drawing, in which,—

Figure 1 is a top view of my improved elevator seen in the elevator shaft in a floor, and adjacent gravity conveyers upon the 30 floor for moving boxes to and from the elevator. Fig. 2 is a vertical section on the line *a a* in Fig. 1, or it may be called a side elevation of my elevator with one side frame removed, and shown as applied to two floors 35 of a building, the floors being in section. Fig. 3 is a fragmentary bottom view of one of the platforms or cars of the elevator. Fig. 4 is an end view of one of the two frame bars 6 in Figs. 1 and 2, with adjacent parts. 40 Fig. 5 is a sectional view on the line *b b* in Fig. 4, of the tenon 23, with tension screw therein. Fig. 6 is a sectional side view of my invention, taken on the line *a—a* of Fig. 1, showing a gravity carrier applied to upper and lower floors of a building.

45 Referring to the drawing by reference numerals, 1 designates the first floor and 2 is one of the upper floors of a building, while 3 is the bottom of a pit sufficiently lower 50 than the first floor to allow the elevator to descend and load from the first floor.

In the hatch-way or shaft 4 is secured a suitable frame consisting of the base timbers 5, horizontal timbers 6, 7, 8 and four

upright posts 9 secured to said other timbers 55 and to the joists 10 of the building. In the upper end of the frame are journaled in bearings 11 two horizontal studs or stump-shafts 12, and in bearings 11^a are fixed two studs 13, while in the bars 6 are fixed four 60 studs 14. Upon the studs 13 and 14 are journaled grooved sheaves 15, over which are stretched two endless chains 16, which are further stretched and also operated by two sprocket wheels 17, fixed on the stump-shafts 12; and the latter are rotated by gear wheels 18 fixed on their outer ends, and two smaller gears 18^a meshing therewith and fixed on a shaft 18^b, driven by a sprocket-wheel 18^c fixed on it, and a belt-chain (not 70 shown), or any other suitable means of transmitting power to said shaft.

The slack in the chains caused by wear is taken up by the tension screws 19, threaded in lugs 20 on the posts 9 and having their 75 lower ends provided with annular grooves 21 engaging a pin 22 in the projecting tenons 23 of the frame bars 6 which are adjustable vertically in slotted mortises 24 in the posts. All four of the tenons 23 are 80 shown in their positions in Fig. 1, and the detail construction of each is clear in Figs. 1, 4 and 5.

The elevator cars or platforms 25 are pivotally suspended by their bracing hangers 26 from horizontal bars 27, which have 85 their ends secured to the chains. Only three cars are shown in the present drawing, but their number will in actual use be decreased or increased according as the height of the 90 building and other circumstances may require. The form of the car may also be varied from the one shown, which is mostly a suspended platform with rollers 35 for the boxes of goods to move on.

95 The lower end of each car is guided by ribs or strips 29 are fixed one on each of the posts 9, and double-flaring guides 30 and 31 fixed on the car and straddling alternately the strips at opposite sides of the elevator shaft, the guides 31 doing service during the ascent and the guide 30 during the descent of the car. To assist the guides on the cars into proper engagement with the strips 29 on the posts I provide on the frame-work the 100 curved guides 32, 33, of which 32 touches the guide 31 as in the left upper part of Fig. 2, when the car starts to descend, and 105

33 guides 31 as in the lower right hand corner of Fig. 2 when the car is to ascend.

Each car has its bottom or platform formed with several bars 34, in which are 5 journaled the ends of rollers 35 in such a manner that in two opposite edges of the platform are formed gaps 36, 36^a, which straddle the ends of gravity conveyers 37, 37^a resting upon each floor of the building 10 and having a folding section 38, pivoted at 39 and provided with a rocker arm 40, from which extends downwardly into the next story a rope or chain 41 with a loop 42, adapted to be placed on a peg 43 and thus 15 hold the section 38 idle in an upright, or slightly inclined position, as shown to the left in the drawing, and when the loop is removed from the peg the section 38 will fall into a straight line with the main body of 20 the gravity conveyer and thus be ready for service.

It will be seen that both the conveyers and the bottom of the car incline in the same direction, so that a box placed upon the 25 rollers of the conveyer 37^a on any of the floors will be moved by its own weight against the stop 44, and as soon as it is picked up by the car it moves of its own weight to the middle of the platform, where 30 it stops against two vertically slideable pegs 45, which are pivotally secured to a lever 46 (see Fig. 3) pivoted in lugs 47 below the platform and having a tail 48 which is held by frictional contact of a spring-arm 49 35 fixed under the platform, until it touches the bracket 50 on the frame, which tilts the lever and draws the pegs 45 downward, so that the moment the car commences to descend the box moves from its central position 40 51 to the position 52, stopping against the fixed catches 53 where it remains until the platform descends from under it, leaving it to rest on a conveyer section 38, which on the desired floor is lowered into position, 45 resting upon the support 54; and when the box is thus deposited it will of its own gravity move away from the elevator as far as the conveyer 37 is arranged to carry it. The pegs or catches 45 are restored upward 50 to normal position by the contact of the tail 48 against the bracket 50^a as soon as the car commences to ascend.

From the above description, it will be seen that I provide an economical elevator both 55 as to construction and operation; everything being simple to make, and as to operation the elevator will load any box or similar article moved near it into proper position, and by means of the cords 60 indicated by 41 the operator may stand on one floor and send goods and deposit them on any of the other floors. The elevator may also be used without gravity conveyers on the floors of the building.

65 Having thus described my invention, what

I claim as new and desire to secure by Letters Patent, is;—

1. In an elevator of the class described, a car having an inclined floor or platform with rollers for the goods-conveying box to rest and move on, fixed guards 53 near the lowest edge of the platform and vertically movable guards 45 retaining the box on the middle of the platform until it commences to descend, and means operated automatically by the motion of the elevator to withdraw the movable guards when the platform or car commences to descend, and restoring the guards again to normal position when the car commences to ascend, and automatic means for holding the guards in active and inactive position. 70 75 80

2. In an elevator of the class described, the combination with an upright frame having four corner posts and horizontal bars at top and bottom and two intermediate horizontal bars having vertical play, means for adjusting said bars vertically, a pair of chain pulleys revolving on studs fixed in each of said adjustable bars, chain-supporting pulleys mounted in the upper end of the frame, one vertically above each of the four lower pulleys, a pair of endless chains running parallel over said upper and lower pulleys, horizontal bars having their ends 90 supported in the chains, elevator cars pivotally suspended from said bars, means for guiding the lower part of each car, two of said chain pulleys being sprocket wheels by which to engage and move the chains, a shaft fixed in said sprocket wheels and journaled in the frame, and means for transmitting power to said shaft, said guiding means for the car consisting of guiding strips 29 fixed one on each post of the frame 100 105 beyond the pathway of the chains, up and downwardly flaring guides 30, 31 upon two opposite sides of each car, the guides 30 being adapted to straddle the strips or ribs on the post during descension and the guides 110 31 during the ascension of the car, and the guides 32 and 33 for guiding the car into sliding engagement with the ribs on the posts. 110

3. An elevator having a frame with two 115 path-ways, one for ascension and one for the descension of cars, a pair of endless chains guided and moved by pulleys or wheels so as to run up one pathway and down the other, and horizontally between 120 the upper ends and between the lower ends of the pathways, horizontal bars having their ends carried by the chains, cars suspended from said bars, guides on the lower ends of the cars, vertically extending guiding strips in the pathways for the guides on the car to move on, and auxiliary guides on the frame work for guiding the cars into each pathway, substantially as and for the purpose set forth. 125 130

4. In an elevating apparatus, the combination with an upright frame, of an elevating belt operating vertically in said frame, a carrier hung from said belt provided with
5 an inclined floor and stop, and adapted to pick up packages on one side and deliver them on the other side of said belt, guides between said frame and carrier, a gravity receiving and delivery conveyer on the sides
10 of said belt and intercepting the path of

said carrier, and means for automatically removing said stop from the path of the article when said carrier co-incides with said receiving conveyer.

In testimony whereof I affix my signature, ¹⁵ in presence of two witnesses.

JOHN HEIMER.
